UNITED STATES PATENT OFFICE

2,589,366

MACHINE FOR HOOPING TUBES

René Gauthier, Brussels, Belgique, assignor to
 Société Continentale et Coloniale de Construction, Société Anonyme, Brussels, Belgique

Application March 29, 1946, Serial No. 658,239
 In Belgium May 16, 1941

Section 1, Public Law 690, August 8, 1946
 Patent expires May 16, 1961

3 Claims. (Cl. 242—11)

1

The present invention relates to machines for hooping tubes, for example of concrete, and relates particularly to a device adapted to maintain the metal hooping wire under constant tension, which is predetermined and without load of inertia, irrespective of the variations in peripheral speed between the tube to be hooped and the means for driving the wire which may be produced during the winding.

According to the invention a hydraulic device for tensioning the wire to be hooped is maintained automatically under predetermined constant pressure and is supplied by a compressor with two identical pumps each actuated by one of the planet wheels of a differential driven by a motor.

A preferred example of construction of the invention is described hereinafter, with reference to the accompanying drawing.

In this drawing, a motor M, preferably electric, actuates a driving pinion 1 of a differential 2 of which the planet pinions 3 and 4 respectively drive the pumps 5 and 6, of an oil compressor. Preferably the pumps are of the gear type and are of equal output.

The planet pinion 4 also drives a pinion 7 which actuates, by means of the pinion 8, a train of special grooved pulleys 9 secured to a shaft 10 and located opposite pulleys 11 loose on a shaft 12.

The oil from a refrigerated tank R is drawn by the pumps 5 and 6 of the compressor and is forced under pressure into pipes 13 and 14, provided respectively with valves 15 and 16, with manual adjustment, and reaches a collector conduit 37 from which the oil is directed into a cylinder 17 arranged vertically so that the liquid enters under the piston 18. The liquid is caused to enter the cylinder below the piston in order to avoid any load of inertia during variations in volume of the liquid in the cylinder.

The oil then leaves the cylinder 17 through the pipe 19, passes through a device 38, herein-after described and which serves for the adjustment of the pressure of the oil in the circuit.

When leaving the device 38, the oil returns to the tank R through the pipe 20. A gauge 21, placed on the pipe 19 in advance of the device 38, indicates the pressure of the oil in the hydraulic circuit.

From the collector conduit 37, a branch conduit 22 conducts the oil under pressure into a cylinder 23 under a piston 24 which, by means of the rod 25, pushes a roller 26 against a reaction roller 27, between which rollers the hooping wire of steel or suitable metal is passed and is slightly braked.

2

The device 38, serving to obtain the desired pressure in the hydraulic circuit, consists of a double walled cylinder, of which the inner wall is provided with longitudinal openings or ports, the size of which, in use, is controlled by the movement of the piston 29. The piston increases, in its valvular capacity, the size of the openings, when it moves against the resistance of the spring 30 in response to the hydraulic pressure. A screw 31 is provided for adjusting the tension of the said spring 30.

In the cylinder 17, the piston 18 is connected by a rod 32 to a fork 33, between the limbs of which a pulley 34 rotates freely.

The tube 35 to be hooped is rotated by any machine (a type of lathe, for example) actuated by an independent motor 39 and connecting gearing 40 or, if preferred, by a transmission driven by the motor M of the device.

The hooping wire 36, on its entrance into the device forming the subject of the invention, passes, as above described, between the rollers 26 and 27 of the device Y, of which the action is automatically proportional to the necessary

25 pull on the wire so that it does not slip on the first pulley A of the train of pulleys 9. The wire is then wound on the driving pulley A and passes successively on to the loose pulley B of the train of pulleys 11, on to the driving pulley C, on to the loose pulley D, on to the driving pulley E, on to the loose pulley F, on to the driving pulley G, on to the return pulley H, on to the tension pulley 34, on to the return pulley I so as to reach the tube 35. The tension of the wire is obtained by the thrust of the pulley 34 produced by the pressure of oil under the piston 18, which pressure is adjusted by the device 38 and is indicated by the pressure gauge 21. More or less pressure is obtained by tightening or slackening the screw

40 31 which acts on the spring 30 and consequently on the piston 29 which more or less closes the ports 28 thus modifying the cross sectional passage for the oil at the outlet from the cylinder 17.

The peripheral speed of the tube 35 should be 45 exactly the same as that of the driving pulleys 9 of the device. This result is obtained by causing one or other of the valves 15 or 16 to act which, by varying the cross section of the passage of the oil delivered by the corresponding pump, will modify the speed of the planet pinion 4 of the pump 6, of the pinion 7 and of the train of driving pulleys, by means of the pinion 8. By reason of the fact that the pumps 5 and 6 are actuated by the planet pinions of a differential,

50 55 the sum of the deliveries of the pumps of the compressor is a constant, irrespective of the rela-

tive speeds of the planetary pinions amongst themselves, and consequently also the pressure of the oil in the hydraulic circuit is constant. When rotation of the tube 35 is stopped, it is also possible, at the same time, to stop the driving pulleys 9, by closing the valve 16 completely which results in stopping the pump 6, the planet pinion 4 and the pinion 7. The planet wheel 3 then rotates at twice its speed of equilibrium, which maintains the same delivery of oil and also the same pressure as before. When the tube 35 slows down temporarily, before it has been possible to obtain the same slowing down of the driving pulleys 9, by means of the valves 15 and 16, the wire 36 is maintained under the desired tension by the rise, in the cylinder 17, of the piston 18 and of the pulley 34 which acts on the wire 36, whilst the ports 28 of the valve 38 close progressively by the movement of the piston 29 which maintains the pressure in the hydraulic circuit.

When the tube, for any reason, accelerates or decelerates, the tendency of the pinion 18 to be displaced actuates immediately the automatic valve 38 by displacement of its piston 29 which in turn modifies the available cross sectional area of the ports 28.

The appropriate shape of the ports 28 of the valve device 38 produces, by the automatic movement of the piston 29, in one direction or the other, a braking of the passage of oil suitable for maintaining a constant pressure and consequently a determined constant tension of the wire.

After the hooping wire 36 is suitably anchored to the periphery of tube or cylinder 35, and guided successively in the grooves of the pulleys I, 34, H, 9 and 11, as well as between rollers 26 and 27 of drag brake Y, pressure is created in cylinder 17 by starting the motor M while maintaining valve 15 completely open and valve 16 closed. As a result, the circulation of the oil is prevented in conduit 14 which causes the stopping of pump 6 and immobilizes planet pinion 4 and consequently also the train of pulleys 9, whereas oil does circulate through conduit 13 permitting the rotation of the pump 5 and planet pinion 3, driven by the crown 2 and pinion 1 of motor M.

The pressure in the cylinder 17 is then adjusted to a predetermined value by modifying the tension of spring 30 of the device 38 by means of the screw 31. As a result of the working pressure in the vertically disposed cylinder 17, the piston 18 is actuated and the hooping wire 36 is placed under tension through intermediary of pulley 34. Pressure in the cylinder 23 actuates the piston 24 and forces the roller 26 relative to the roller 27 and engaging the wire 36.

Cylinder 35 is then rotated by the prime mover 39 through connecting gearing 40 and the valve 16 is progressively opened which, by permitting oil to flow in pipe 14, effects rotation of pump 6 and consequently of the planet pinion 4 which drives pinions 7 and 8 as well as the set of grooved pulleys 9.

When the valve 16 is opened, valve 15 is likewise actuated so as to adjust the oil passage area in the line 13 of pump 5 in order to impart to the set of pulleys 9 a peripheral speed that is substantially equal to that of the cylinder 35.

If, during the winding of the wire 36, slight variations in length of wire should occur between the unreeling device 9-11 and cylinder 35 and due, for example, to irregularities formed at the periphery of said cylinder 35, the said

variations in wire length will be compensated by the reciprocable movement of the piston 18 in the cylinder 17. These movements of the piston 18 are normally of small amplitude, but if, for any reason whatsoever, the peripheral speed of the unreeling device 9-11 or of the cylinder 35 becomes modified due to an exaggerated reciprocable movement of piston 18 in either direction, it is possible to operate the valves 15 and 16 so as to modify the unreeling speed of the wire 36 so as to bring the piston 18 back to its normal operating position in the cylinder 17.

In order to stop the machine, the valve 16 is closed and the valve 15 opened, while simultaneously stopping the prime mover 39 of the cylinder 35. The wire 36 is thus kept under tension by the liquid circulated by the pump 5, which permits fastening the wire 36 on the cylinder 35 when the winding is terminated. When this last operation is ended the motor M is stopped and the pressure in the machine circuit is relieved by unscrewing of the screw 31 after which the wire 36 is cut at the place where it is attached to the cylinder 33 so as to permit removal of the latter.

What I claim is:

1. A machine for hooping tubes comprising, in combination with a device actuated by motor for driving in rotation the tube to be hooped, a train of grooved pulleys to drive the hooping wire for unwinding, a train of grooved loose pulleys to guide said wire on the driving pulleys, a motor, a differential mechanism actuated by said motor, two shafts to be driven each by one of the planets of said differential, a transmission to connect one of said shafts to the train of driving pulleys, two pumps to be driven each by one of the differential shafts, valves for controlling the output of each of said pumps, a hydraulic piston and cylinder unit fed by said pumps, said unit including a surface adapted to act by tension on the hooping wire extending between the driving pulleys and the tube to be hooped, means for automatically controlling the hydraulic pressure in said unit and means controlled by said pressure to retard the unwinding of the wire before its passage on the driving pulleys.

2. A machine for hooping tubes comprising, in combination with a device actuated by motor for driving in rotation the tube to be hooped, a train of grooved pulleys to drive the hooping wire for unwinding, a train of grooved loose pulleys to guide said wire on the driving pulleys, a motor, a differential mechanism actuated by said motor, two shafts to be driven each by one of the planets of said differential, a transmission to connect one of said shafts to the train of driving pulleys, two pumps to be driven each by one of the differential shafts, an oil reservoir to feed said pumps, a cylinder, conduits connecting said pumps to said cylinder, valves in each of said conduits for controlling the output of said pumps, a piston in said cylinder, a rod on said piston, a loose pulley on the end of said rod to act upon the hooping wire extending between the driving pulleys and the tube to be hooped, an automatic regulator device to control the pressure in said cylinder, a conduit to connect said cylinder to said pressure regulator device, a pressure gauge on the latter conduit, a conduit to connect said pressure regulator to said pumps reservoir, a first roller, supported on a fixed point, on which roller the hooping wire passes before its passage on the driving pulleys, a second roller acting upon said first roller and upon said hooping wire, a second

cylinder, and a piston supporting said second roller, said piston being submitted to the pressure in the first cylinder.

3. A machine for hooping tubes comprising, means for rotating the tube to be hooped, a driven shaft, a train of pulleys fixed on the shaft for unwinding a hooping wire, a train of grooved loose pulleys opposed to the fixed pulleys to guide the wire on the driving pulleys, a prime mover, a differential mechanism operated by the prime mover, a pair of shafts driven by the planets of said differential, transmission means connecting one of the shafts to the driven shaft for the pulleys, pumps driven by the differential shafts, valves controlling the output of each of said pumps, a hydraulic piston and cylinder unit connected to and actuated by said pumps, a pulley carried by the piston rod and having the hooping wire entrained thereon for tensioning the

same, an automatic regulator device for controlling the pressure in the cylinder and the extension of the piston rod from the cylinder, and means connected to and actuated by the output pressure of the pumps for exerting a drag on the wire before its passage on the driving pulleys.
